J. M. MELLIS,

DIRECTION INDICATOR.

FILED MAY 24, 1921.

UNITED STATES PATENT OFFICE.

JAMES M. MELLIS, OF VICTORIA, BRITISH COLUMBIA, CANADA, ASSIGNOR OF ONE-HALF TO WILLIAM H. L. MELLIS, OF PETERBOROUGH, ONTARIO, CANADA.

DIRECTION INDICATOR.

Application filed May 24, 1921. Serial No. 472,158.

To all whom it may concern:

Be it known that I, JAMES M. MELLIS, citizen of the Dominion of Canada, residing at Victoria, in the Province of British Columbia, Canada, have invented certain new and useful Improvements in Direction Indicators, of which the following is a specification.

This invention relates to a direction indicator for self-propelled vehicles and is designed as an improvement on that on which Patent No. 1,321,933 was granted.

The improvements, which are the subject of the present application, are directed to minor details of construction suggested by practical experience in the manufacture of the device, and particularly to an improved indicating hand and the manner of illuminating the same.

20 The invention is fully described in the following specification, reference being made to the drawings by which it is accompanied, in which:

Fig. 1 is an elevation of the device as applied to the windshield of a car, being a view taken from the position of the driver.

Fig. 2 is an enlarged detail section of the indicating hand and its pivotal connection being on the line 2—2 in Fig. 3.

30 Fig. 3 is an inverted plan of the same.

Fig. 4 is a section on the line 4—4 in Fig. 1 and shows the connection of the bracket in which the indicating hand is mounted to the clamp by which it is attached to the windshield frame.

Fig. 5 is an enlarged detail of the operating handle on the control board showing the circuit closing contact of the sound alarm co-operative therewith.

40 As in the previous application the indicating semaphore 2 is preferably contoured to represent a hand, but instead of that hand being represented by a flat surface on the face of which a light is projected at night, it is formed of two embossed plates jointed together in a vertical plane in a manner to leave slits or apertures 3 in the joint between the two faces of the hand, which slits 3 are also left in the edges of the spaces 4

45 between the fingers.

In each face of the hand at the approximate location of the palm is an aperture

which is closed by a removable window 5 of red coloured glass.

Adjacent the wrist this semaphore has a 55 stem 8 secured to it between the two halves, both ends of which stem project as pivots about which the semaphore may turn on a vertical axis in a bearing bracket 9.

This bracket is mounted on an axial pin 60 10 projecting outward from a clamp 11 by which the device is secured to the side frame of the windshield or other convenient position. This manner of mounting the pivot bracket 9 on the pin 10 permits of axial 65 adjustment of the hand to bring the wider dimension of it substantially vertical, when there is a backward rake to the windshield. The bracket 9 is secured in its adjustment by a small screw 12 threaded through the 70 end of the clamp member 11 parallel to the pin 10, which screw has a reduced end which may enter one of a series of small apertures drilled in the face of the bracket 9 to be concentric with its pin 10.

75 The bearing bracket 9 carries a stem 30 on the upper end of which is a clamp 31 adapted to hold a back viewing mirror with provision by which it may be set at any desired angle to suit the driver.

80 On the lower end of the pivot 8 below its bearing in the bracket 9 is secured a small flanged sheave 13 around which a flexible line, such as wire cable, is coiled and made fast. The ends of this wire cable 85 14 are conducted through separate sheathing coils 15 which are themselves enclosed within a tube 16 to another sheave 17 mounted on a pin 18 projecting from a support 20 which is clamped or otherwise secured to the 90 steering post of the car to be convenient for the operator. On this sheave 17 the ends of 14 are made fast. The sheave 17 is provided with a handle 19 by which it may be moved to either side, which movement 95 will correspondingly move the semaphore 2 to either side of the normal forwardly pointing position.

At the back the hub of the sheave 17 is notched as at 21, to receive the end of a retaining bolt 22 endwise movable on the support 20 against the resistance of a spring. The end of the bolt 22 engaging the notches 21 retains the sheave 17 and therefore the

semaphore 2 in the position to which it is set.

This bolt 22 performs a further service in closing an electric circuit to sound a 5 buzzer 24 or other alarm, while the movement of the indicator is being made. This it attained by conducting the wires of the buzzer circuit to terminals 25 which are closed by a contact 26 formed on the end of 10 the bolt 22. Thus, when the semaphore 2 is moved to indicate an intended change of direction the buzzer is sounded.

Within the hollow of the semaphore 2 adjacent the pivotal mounting 8 a small 15 electric light bulb 6 is located with a reflector 7 throwing the light outward into the hand and fingers. The wires 23 of the circuit which serves this lamp, are conducted through the tube 16 to the control 20 board where connection of them is made to the lighting circuit of the car.

In use, the semaphore mounting is clamped, as shown in Fig. 1, to the side standard of the windshield or other convenient position on the car, and the operating mechanism is secured to the control board or steering post to be convenient to the operator. By movement of the handle 19 the indicating semaphore is moved from its normal or straight ahead position to a position 30 at right angles thereto to either side. At night the semaphore is illuminated by the lamp 6, and when the hand is turned to indicate an intended change of direction, that 35 movement is not only intimated by the buzzer or other alarm, but by a red light showing from both sides of the body of the hand and by the light emitted from the outline of the hand and between the fingers.

40 This latter feature forms a distinctive characteristic of the invention which differentiates it from what has heretofore been effected in this line of invention.

Having now particularly described my invention, I hereby declare that what I claim 45 as new and desire to be protected in by Letters Patent, is:

1. A direction indicator, comprising a semaphore adapted to turn on a vertical 50 axis adjacent one end, said semaphore being hollow and constructed in two parts divided in the plane of the axis of its movement with interspaces along the line of the joint, and means located within and near the axis of 55 the semaphore for projecting a light into the hollow of the semaphore and through the slits of the joint.

2. A direction indicator, comprising a semaphore adapted to turn on a vertical 60 axis adjacent one end, the contour of which semaphore represents a hand which is constructed in two outwardly convex embossed parts divided in the plane of the axis of movement, the joint of the two parts having

interspaces around the outline and between 65 the fingers, and means for projecting a light from adjacent the axis of movement into the hollow of the hand and through the slits of the joint.

3. A direction indicator, comprising a 70 member adapted for attachment to an automobile, a bearing bracket pivotally mounted on this member to provide for angular adjustment about a horizontal axis, the bearings of said bracket being in a substantially 75 vertical axis, a semaphore having pivots adjacent one end adapted to fit the bearing of the bracket, a flanged sheave secured to one of the pivots of the semaphore, a flexible line secured to the sheave, means for conducting both ends of the flexible line to a position convenient to the operator, and means mounted at such position for pulling one flexible line and correspondingly releasing the other.

4. In a direction indicator, a semaphore contoured to represent a hand and formed of two parts divided in the plane of the axis of movement with a cavity between the parts, and slits in the joint at intervals 90 around the contour of the hand, means for projecting a light into the hollow of the hand, and means for imparting movement to the semaphore.

5. In a direction indicator in which is 95 provided a pivoted visual indicating signal and an audible indicating signal; a means for operating the aforesaid signals, said means comprising a flanged sheave secured to the visual signal, a flexible line secured 100 to and coiled on the sheave, both ends of which line are conducted together through separate tubes to the place of operation, a grooved sheave to which the ends of the line are secured, which sheave is rotatably 105 mounted on a pivot secured at a position convenient to the operator, resilient means locating the position of the operating sheave when the visual signal of the indicator is "forwardly" directed and for locating it at 110 right angles to that position to either side, and means cooperative with said locating means for effecting operation of the audible signal of said indicator when the visual signal of said indicator is moved from the 115 "forward" position to either side.

6. A direction indicator comprising a clamping member adapted for attachment to an automobile windshield support, a bracket member pivotally adjustable on a 120 horizontal axis on said clamping member, a semaphore having pivots at one end adapted to fit bearings in said bracket whereby said semaphore may be pivotally moved on a vertical axis, means for moving the semaphore on its axis, said semaphore comprising a "hand" having a wrist portion and composed of bowed front and back plates 125

secured together, an illuminant within the wrist portion of said "hand," said "hand" having a removable window in each face with colored glass for the purposes specified.

7. In a direction indicator, a signal hand with wrist portion comprising two bowed plates secured together along one edge, said plates having the outline of a hand and fin-

gers with open slits between the fingers and 10 having windows, an illuminant located in the wrist portion of the hand between said plates to project the light longitudinally of the hand toward the fingers, means for pivotally mounting said hand and means for 15 moving it on its pivot.

In testimony whereof I affix my signature.
JAMES M. MELLIS.
